UNITED STATES PATENT OFFICE

CARL D. BROWN, OF HOPEDALE, MASSACHUSETTS, ASSIGNOR TO DRAPER CORPORATION, OF HOPEDALE, MASSACHUSETTS, A CORPORATION OF MAINE

SHIFTING SHUTTLE BOX LOOM

Application filed August 6, 1928. Serial No. 297,685.

This invention relates primarily to a shifting shuttle box loom, more particularly designed for use in the weaving of rayon, silk and similar fabrics.

- 5 One object of the invention is to provide a simple and efficient principle of construction for shifting transversely a plurality of shuttle boxes at the end of the lay to bring either into alignment with the lay.
- 10 Another object of the invention is to provide a picking mechanism in which absolute rectilinear movement of the shuttle across the lay is insured and in which the shuttle is picked in a right line parallel with the race-way.

Another object of the invention is to provide a picking mechanism employing a single picker stick with means for shifting the picker stick into cooperation with the active shuttle and out of cooperation with the inactive shuttle whenever a shift of the shuttle boxes occurs.

Another object of the invention is to provide a practical form of transversely, shifting shuttle boxes adapted to cooperate with a filling replenishing mechanism of the well-known Northrop type.

These and other objects and features of the invention will appear more fully from the accompanying description and drawings and will be particularly pointed out in the claims.

The drawings illustrate a preferred form of the invention as applied to a two-shuttle loom particularly designed for weaving rayon fabrics. As the invention relates only to certain features of the loom and as the other features making up the loom may be of various forms well known to those skilled in the art, it is only necessary to illustrate so much of a loom as is necessary to a disclosure of the present invention.

In the drawings:

Fig. 1 is a view in front elevation, partially in vertical cross section and partially broken away, of the right-hand or shifting shuttle box end of the loom showing a preferred form of the invention embodied therein.

Fig. 2 is a side elevation, partially in ver-

tical cross section and partially broken away, of the construction shown in Fig. 1.

Fig. 3 is a view in general similar to Fig. 2, but showing the parts in a different position.

Fig. 4 is a detail in horizontal cross section on the line 4—4 of Fig. 3.

Fig. 5 is a detail in end elevation and partially in cross section of a give-way connection in the mechanism for shifting the picker stick.

Fig. 6 is a top plan view showing the adjacent ends of the main and box lay sections.

Fig. 7 is a detail of a portion of the construction shown in Fig. 6 taken in vertical cross section through the middle of the shuttle throat.

Fig. 8 is a view of a portion of the construction of Fig. 6 taken in horizontal cross section.

The loom, including the frame, the right-hand side member 1 of which is illustrated, the lay rock shaft 2 carrying the lay supporting swords 3, the reed 4, the crank shaft 5 with its cranks 6, the pitmen, one of which is shown at 7, the shaft 8 operating the pick motion, are in general of any ordinary and usual construction and the loom is also provided with the other usual features and adjunctive devices necessary to its operation and which may be of various types familiar to those skilled in the art.

In the construction illustrated, the lay presents a main section 9 supported in the usual manner by the swords 3 and given its usual swinging movement from the pitmen 7. The raceway 10 for the active shuttle extends across the loom on the top face of this main lay section. At the right-hand end the lay also presents a transversely shiftable box section 11 which carries a plurality of shuttle boxes herein shown as two in number. These boxes are formed by a central member 12 which forms one wall of each box and by the outer wall members 13 and 14 equipped with suitable binders 15 and 16, respectively. This box lay section is supported from and swings both with, and with respect to, the lay rock shaft 2. This box lay section is also held in close contact with the main lay section both

when it moves with the main lay section and when it moves with respect thereto for shifting the shuttles. The construction is such that the shuttle boxes are shifted transversely 5 so that the shuttles 17 and 18 are located with their open sides at the top and bottom, thus enabling filling replenishment to be effected by means such as is employed in the well-known Northrop loom. The box lay section 10 is accurately supported and guided in its shifting movement with each box at all times in parallelism with the raceway. In addition, the picking mechanism operates upon a principle which ensures each shuttle being 15 moved in vertical parallelism with the raceway. Thus any danger of marking or injuring fine fabrics such as rayon by the jumping of the shuttle when picked from its box or during its passage across the lay is eliminated.

In the preferred construction illustrated for securing these results, the box lay section is supported by an auxiliary sword carried by the usual shoe on the end of the lay rock 25 shaft. This shoe 19, instead of being made fast to the lay rock shaft 2, is journaled thereon between the hub 20 secured to the shaft 2 by a set screw 21, and a collar 22 secured to the shaft by a set screw 23. A bracket arm 24 extends upward from the shoe 19 and the main body member 25 of the auxiliary sword which is centrally offset to avoid the pick motion, is adjustably secured at its lower end to this bracket arm, first, by 30 a bolt 26 passing laterally therethrough and, second, by a set screw 27 extending vertically through a lug 28 on the member 25 and abutting the upper end of the arm 24. This set screw may be adjusted and held in adjusted 35 position by the lock nut 29. At its upper end the auxiliary sword member 25 is similarly adjustably connected by the bolt 30 and set screw 31 to a vertical flange 32 extending down from the inner end of the lay box section 11.

The accurate alignment of the main and box lay sections 9 and 11 at all times results from the fact that each is provided with extended smooth abutting faces and that means 50 are provided which extend through and hold these abutting faces in contact, while at the same time permitting the necessary shifting movement. For this purpose the main lay section is shown as provided with flanged 55 brackets 33 at the front and 34 at the rear secured in place by the bolts 35. The flanges 36 and 37 present at the end of the main lay section an extended smooth vertical face. The end of the box lay section with the depending and extending flange 32 presents an 60 oppositely disposed vertical smooth face and these two faces, the one on the main lay section and the other on the box lay section, abut each other, thus serving to guide the box lay section in its shifting movement. These

abutting faces are held in contact, first, by a bolt 38 secured in the flange 32 of the box lay section at the front and passing through an arcuate slot 39 in the flange 36 with its center of curvature at the axis of the lay rock shaft 2, and, second, by a bolt 40 at the rear, the construction and operation of which will later be described.

Any suitable mechanism may be employed for effecting the transverse shift of the box lay section with respect to the main lay section to bring either shuttle into action at predetermined times and maintain it in action during predetermined periods. With the simple form of the invention here illustrated, 70 the shuttles are shifted at regular intervals and remain in action for regular periods and it is sufficient, therefore, to illustrate a cam mechanism for shifting the box lay section and retaining it in shifted position, but this mechanism is only illustrative.

In the form thus illustrated, the box lay section is directly shifted by a bell crank lever fulcrumed at 41 on a lug 42 projecting rearwardly from the main lay section. This bell crank lever comprises a downwardly extending arm 43 and a rearwardly extending arm 44. The arm 43 carries at its lower end the bolt 40, already described, which swings through an arcuate slot 45 in the flange 37 on the end of the main lay section, this slot 45 having its center of curvature at the fulcrum axis 41. This bolt carries a slide block 46 sliding in a vertical way in the flange 32 of the box lay section. Thus it will be seen that as the bell crank lever 43 and 44 is rocked, the box lay section will be shifted and that by holding the bell crank lever in fixed position with respect to the main lay section, the box lay section will also be held in fixed relation to the main lay section.

In the construction illustrated, this bell crank lever is controlled by a cam member which is bodily shifted to rock the bell crank lever and thus shift the box lay section relatively to the main lay section and which in either position holds the bell crank lever against rocking movement with respect to the main lay section during the swing of the lay. This cam member is shown as a slide plate 47 provided with a cam groove 48 having the walls 49 and 50. The plate 47 is mounted to slide vertically in ways 51 secured to the loom frame. The arm 44 of the bell crank lever is provided at its end with a roller follower 52 riding in the groove 48.

The cam member 47, in the construction illustrated, is shifted and retained in position by a cam conveniently driven from the shaft 8 carrying the pick cam. This shaft 8 is shown as carrying a pinion 53 meshing with a gear 54 journalled at 55 on the loom frame. A cam groove 56 is cut in the face of the gear 54 and is here shown illustratively as of a form which will shift the box lay sec-

tion at equal and regular intervals and retain each shuttle in active position for a similar period. The cam groove 56 operates the cam member 47 through a riser comprising the plate 57 and the rod 58 adjustably secured in a recessed portion of the plate by the set screws 59. The plate 57 is slotted at 60 to slide and guide on the journal 55 of the gear 54 and has journalled on one face a roll follower 61 riding in the cam groove 56. The rod 58 fits at its upper end in the vertical bore of a rib 62 on the cam member 47 and is secured thereto by a give-way connection shown in detail in Fig. 4. A plunger 63 is mounted to slide transversely in a horizontal rib 64 on the cam member 47 and is pressed inwardly by a spring 65. This plunger has a bevelled nose 66 fitting a recess in the side of the rod 58. Normally, therefore, the cam member 47 is locked to the riser and thus controlled in its movement and position by the cam groove 56, but if a shuttle is not properly boxed or anything happens to hold the box lay section against shifting movement when required, a smash or breakage will be prevented by this give-way connection.

In the control of the box lay section, with the mechanism illustrated, the non-circular portions of the cam groove 56 act to give the shifting movement by raising or lowering the cam member 47 and thus rocking the bell crank lever 44, 43 from one extreme position to the other. The box lay section is held in fixed position with respect to the main lay section after each shift because the follower 61 then rides in one or the other of the circular portions of the cam groove 56, thus holding the cam member 47 in fixed position, while the cam groove 48 is so constructed as to prevent any rocking movement of the bell crank lever 44, 43 during the swing of the lay when the cam member 47 is in fixed position. This result is secured by making that wall of the cam groove 48 against which the follower 52 rides concentric with the axis of the lay rock shaft 2 about which the main and box lay sections swing. In Fig. 2 the parts are shown at the conclusion of the shift of the box lay section to render the shuttle 18 active with the cam member 47 in its lowermost position. With the lay swinging with the parts in this position, the follower roll 52 will ride against the wall 49 of the groove 58 and this wall when in this position is concentric with the axis of the rock shaft 2. In Fig. 3 the parts are shown with the box lay section shifted to render the shuttle 17 active. Consequently the cam member 47 is in its upper position and the follower roll 52 rides against the wall 50 and this wall in this position is consequently made concentric with the axis of the rock shaft 2.

In the construction thus illustrated as a preferred embodiment of the invention, it will be seen that the box lay section through-

out its shifting movement is held by reason of the extended opposed contacting end faces and the connecting sliding bolts in accurate alignment with the main lay section and that each shuttle box at the end of the shift is brought into and maintained in an accurate alignment with the raceway of the main lay section. In the preferred construction, there is a single shuttle guiding throat at the end of the main lay section directing the shuttle into whichever of the shuttle boxes is in alignment with the raceway. This throat is shown as comprising a downwardly inclined upper wall 67 covered with a suitable leather facing 68 and front and rear walls 69 and 70 by which the shuttle is guided into the aligned shuttle box at the conclusion of the pick.

The mechanism for picking the active shuttle of this invention is designed to insure absolute rectilinear movement of the shuttle parallel with the raceway and to prevent any deflection of the shuttle from such a path. This is particularly important in connection with the weaving of rayon and silk fabrics which are frequently injured by the shuttle being projected slightly upward by the picker mechanism. The invention in its preferred form provides a picker for each shuttle box accurately guided in parallelism with the raceway and a single picker stick shifted as required into engagement with the picker of the active shuttle and out of engagement with the picker of the inactive shuttle and in the preferred form of the invention, the shifting movement of the picker stick from one picker to another is controlled by the relative movement between the main and box lay sections.

A simple and preferred form of picker mechanism embodying these and other features of the invention is illustrated as applied to the shifting box lay section having two shuttle boxes. A picker rod is mounted upon the box lay section beneath each shuttle box in accurate parallelism with the raceway, the picker rod 71 being shown beneath the front shuttle box and the picker rod 72 beneath the rear shuttle box. The bottom of each shuttle box and the box lay section underneath is provided with a slot such as 73 and 74 extending therethrough and normal thereto in parallelism with the corresponding picker rod. Pickers 75 and 76 are provided for each shuttle box. These pickers at their lower ends slide on the respective rods 71 and 72, extend vertically upward through the respective slots 73 and 74 and have their heads opposite the shuttle noses. Consequently it will be seen that as these pickers are guided in accurate parallelism with the raceway, they will, when moved, have no tendency to deflect the shuttle from a path accurately parallel with the raceway during the picking movement and will thus insure accuracy of the travel of each shuttle across the lay.

The lay rock shaft 2, as already noted, is provided with the shoe 19 journalled thereon between the hub 20 and the collar 22 and swinging with the box lay section. This shoe at its outer end is provided with the upper face 77 on which rests the rocker 78 to which is rigidly secured in the usual manner, as by the bolt 79, the picker stick 80. The lower face 81 of the rocker 78 is curved longitudinally in the usual manner so that as it rocks on the face 77 of the shoe, the upper end of the picker stick will move in a substantially horizontal path. But in the present invention the picker stick rocks transversely with respect to the shoe and the face 81 of the rocker is curved transversely also to permit this rocking movement. While the upper face of the shoe is illustrated as flat and parallel with the rock shaft and the lower face of the rocker as curved both longitudinally and transversely, it is sufficient that these cooperating faces be relatively curved both longitudinally and transversely to permit the upper effective end of the picker stick to move in substantial parallelism with the rock shaft in either of the transverse pluralities of positions required for its cooperation with the pickers. The usual tongue 82 is shown extending up from the shoe 19 through a slot in the rocker 78. At its upper end the picker stick is provided with pins 83 extending transversely from either side and engageable with slots 84 in the pickers so that as the picker stick is swung transversely with respect to the box lay section one pin will be brought into engagement with the picker for the active shuttle and the other pin will be withdrawn from engagement with the picker of the inactive shuttle.

A guide is provided for the upper portion of the picker stick extending parallel with the raceway and mounted on the box lay section to move transversely thereof and thus shift the picker stick from the picker of the inactive to the picker of the active shuttle and, as already pointed out, this guide is moved transversely upon the movement of the box lay section with respect to the main lay section. This guide is shown as comprising a pair of parallel bars 85 and 86 secured at their ends by bolts 87 in spaced relation and between which the picker stick swings. The inner surfaces of these bars are formed on a convex curve so that both bars may maintain a light contact with the picker stick in all positions. At each end one of the bars, as 85, is provided with upstanding arms 88 journalled on an axis extending parallel with the raceway. The outer arm 88 is shown as 60 journalled to a bracket 89 depending from the outward end of the box lay section, while the inner arm is journalled on a stud 90 secured to and projecting from the flange 32 of the box lay section. In the construction 65 illustrated, the outer arm 88 forms a portion

of a bell crank lever having an arm 91 projecting rearward. A link connects the arm 91 with an arm projecting radially from and secured to the lay rock shaft 2 and these parts are so proportioned that as the box lay section is shifted with respect to the main lay section to shift the shuttles, the picker stick guide will be rocked to shift the picker stick from one picker to another. The link is shown as comprising a rod 92 threaded at its ends into turnbuckles 93 and 94 whereby it may readily be adjusted. The upper turnbuckle 93 is pivoted by the bolt 95 to the arm 91, while the lower turnbuckle 94 is pivoted to the arm secured to and projecting from the lay rock shaft. This latter arm is so constructed as to form a give-way connection which will prevent a smash if, for example, the picker is not in position when the picker stick is shifted by the guide. This construction is shown more in detail in Fig. 5. A bifurcated member 96 projects radially from the hub 20 already described as secured to the lay rock shaft 2 by the set screw 21. The bifurcations 97 of this member are each bifurcated transversely at their ends and provided with journal pins 98. A V-shaped member 99 has its free ends recessed to fit over the pins 98 and is pivoted at its center at 100 to the turnbuckle 94. A coiled spring 101 is secured at one end to the member 99 and at the other end to the member 96 extending between the bifurcations 97. This spring under normal conditions holds the members 99 and 96 together as a single arm projecting from and secured to the rock shaft. If, however, the upper end of the picker stick is restrained from swinging, the slotted guide is also restrained from swinging, the link 92 is held against movement and consequently as the shaft 2 rocks, the member 96 gives way, swinging about one of the pins 98 and elongating the spring 101.

The swinging movements of the picker stick in the picking and shuttle checking operations may be secured by any suitable means and are herein shown as secured by a generally old type of means, except that in this specific form of the invention the latter portion of the return movement of the picker stick is positively effected so as to insure alignment of the pickers with the picker stick when the picker stick shifts from one picker to another. In the construction illustrated, the picker stick is yieldingly swung outwardly by the usual strap 102 secured thereto and extending down through the shoe to the drum 103 yieldingly wound up by the usual spring 104 and mounted on the stud 105 beneath the shoe. The pick motion is shown as comprising the usual pick cam 106 on the shaft 8, the pick shaft 107 journalled on the loom frame having one arm 108 provided with a pick ball or tappet 109 running on the cam 106 and the other or pick arm 110 connected 120

to the usual lug strap 111 extending to the picker stick. In this case, however, the lug strap at its inner end presents a shoulder 112 abutting the inner face of the picker stick. A cam plate 113 is also mounted on the pick cam 106 by means of the bracket arms 114 so as to extend at a distance equal to the diameter of the pick ball 109 from the periphery of the pick cam 106 throughout that portion thereof that controls the final outward or return movement of the picker stick. Thus it will be seen that not only is the picker stick given its usual picking movement, but it is positively returned at the outer end of its return movement, thus insuring proper alignment of the pins 83 with the slots 84 in the pickers at all times when a shift may occur.

A picker stick check of a usual type is illustrated comprising a flexible loop member 115 sliding in the bracket 116 against suitable friction and acting to check the movement of the picker stick.

A suitable protector mechanism is provided of a generally familiar type to stop the loom in case the active shuttle is improperly boxed. This mechanism is shown as comprising protector fingers 117 and 118 cooperating respectively with the binders 15 and 16 fulcrumed respectively at 119 and 120 on the flange 32 of the box lay section. Suitable springs 121 hold these protector fingers in engagement with the binders. An arm 122 extends rearward from the finger 117 and a similar arm 123 extends forward from the protector finger 118. When the box lay section is shifted, the arm 122 or 123 of the protector finger for the shuttle box shifted into active position is moved beneath a lug 124 extending from the usual dagger 125 pivoted to the main lay section. Consequently, whichever shuttle box may be in active position, if the active shuttle is improperly boxed, this dagger will be allowed to drop and effect the stopping of the loom in a manner well known to those skilled in the art.

The invention also provides for the accurate assembly and adjustment of the shuttle boxes on the box lay section and the shuttle guiding throat on the main lay section so that these elements will cooperate accurately, be adaptable to variations in the size of the shuttles and insure proper alignment after each shift of the shuttle boxes. Certain specific constructions for specifically securing these and other associated features of the invention are shown on a larger scale in Figs. 6 to 8, inclusive.

The rear wall member 14 is transversely adjustable on the box lay section 11 by means of bolts 126 extending through slotted lugs 127 of the wall member and into the section. A similar transverse adjustment is provided for the front wall member 13 in this case by means of cap screws 128 extending up

through slots in the section 11 into a flange of the wall member. It is desirable that the central wall member indicated as a whole at 12 should have each wall surface adjustable transversely so that each shuttle box may be made of the desired width. For this purpose this wall member 12 is made in two longitudinal sections 129 and 130 having their abutting ends bevelled as at 131 and 132 and one set of bevelled ends as at 132 being serrated. Thus by shifting these sections longitudinally, the width of the central wall member 12 as a whole is adjusted transversely. Suitable bolts 133 extending transversely through slots in the two sections act to secure them together in adjusted position. Then the member 12 is secured to the lay section by bolts 134 passing through enlarged openings therein and thence into the lay section. Thus there is provided a simple means for adjusting the width of the central wall member 12 and therefore of each of its wall surfaces with respect to the opposed wall surface on the members 13 and 14 and then for securing the central wall member in position on the lay section.

The shuttle guiding throat already referred to having the top wall 67, the front wall 69 and the rear wall 70 also contains in its preferred form certain features such as shown in Figs. 6 and 7. Therein the top and rear walls 67 and 70 are formed of one piece of metal having a base 135 with bevelled edges 136 set into a bevelled edge recess in the standard 137, which forms the upper end of the sword 3 and which supports the reed 4, and is locked in place by a bolt 138. The front wall 69 of the shuttle guiding throat is adjustably secured in place to the main lay section by bolts 139 extending through enlarged openings therein into the lay section. The face of this member is also preferably covered at least throughout its main portion with a leather facing 140.

It is desirable that means should be provided for insuring that the shuttles be well within their boxes whenever the box lay section shifts with respect to the main lay section and for that purpose the ends of the shuttle guiding throat are curved to push back into the box any shuttle projecting slightly therefrom. For this purpose the rear wall 70 is shown curved at 141 and the front wall is provided with an end section 142 longitudinally adjustable on the main section by means of a bolt 143 and the cooperating serrated faces 144. This end section 142 also presents a curved face 145 which may thus be accurately positioned to assist in pushing back any slightly mispositioned shuttle.

Further to assist in the accurate alignment of each shuttle box with the raceway when shifted into position to align therewith, an adjustable stop feature is provided shown

in the preferred construction in Fig. 8. Herein the main lay section is provided at the rear with a bracket plate 146 secured thereto and at the front with a similar plate 147 secured thereto behind the flanged bracket 33. These plates project outwardly beneath the overhanging portion of the box lay section 11 and are each provided with transversely adjustable stop screws 148 and 149, respectively, held in adjusted position by suitable lock nuts 150. The box lay section has integral therewith and extended between these stop screws a lug 151. Consequently it will be seen that by adjusting the stop screws so that the lug 151 will contact therewith when the corresponding shuttle box is in alignment with the shuttle throat, the accuracy of such alignment will be maintained under all conditions.

Having thus described the invention, what is claimed as new, and desired to be secured by Letters Patent, is:

1. A loom comprising a lay having a main section with a raceway and a transversely shiftable box section, a plurality of shuttle boxes on the box lay section, any one of which may be aligned with the raceway by shifting the said section, a picker rod for each box mounted upon the box lay section in parallelism with the raceway, a picker slideable on each picker rod, and means for effecting the picking movement of each picker when its shuttle box is aligned with the raceway, whereby under all conditions the active shuttle is projected in a straight line parallel with the raceway.

2. A loom comprising the construction defined in claim 1, in which the bottom of each shuttle box and the box lay section therebelow has a slot extending therethrough and normal thereto in parallelism with the corresponding picker rod for guiding the upper part of the corresponding picker.

3. A loom comprising the construction defined in claim 1, in which the main lay section is provided at its end adjacent the shiftable box section with a single shuttle guiding throat with which any one of the shuttle boxes cooperates when brought into alignment with the raceway.

4. A loom comprising a lay having a main section with a raceway and a transversely shiftable shuttle box section, a single shuttle guiding throat at the end of the raceway on the main lay section, and a plurality of shuttle boxes on the box lay section, any one of which may be aligned with the said throat and the raceway by shifting the box lay section, the width of the throat and of each shuttle box being substantially the same so that the throat acts to guide the shuttle accurately into the box aligned therewith.

5. A loom comprising a lay having a main section with a raceway and a transversely shiftable shuttle box section, a single shuttle

guiding throat at the end of the raceway on the main lay section, a plurality of shuttle boxes on the box lay section, any one of which may be aligned with the said throat and the raceway by shifting the box lay section, the adjacent ends of the main and box lay sections each presenting extended smooth abutting faces, and means extending through and holding said faces in contact while permitting the shifting movement of the box lay section.

6. A loom comprising a lay having a main section with a raceway and a transversely shiftable box lay section, the said main and box lay sections having their adjacent ends each presenting extended smooth abutting faces, means extending through and holding said faces in contact while permitting the shifting movement, and a plurality of shuttle boxes on the box lay section, any one of which may be aligned with the raceway by shifting the said section.

7. A loom comprising a lay rock shaft, a main lay section having a raceway supported by and swinging with said shaft, a shuttle box lay section supported to swing with, and with respect to, the main lay section, a plurality of shuttle boxes on the box lay section, any one of which may be aligned with the raceway by shifting the said section, means for swinging the main lay section and therewith the box lay section, means for swinging the box lay section at predetermined times with respect to the main lay section to shift either shuttle box thereon as required into alignment with the raceway, and a picker stick carried by the lay rock shaft mounted to swing longitudinally of the shaft to effect the picking movement and also to swing transversely with, and with respect to, the box lay section to cooperate with the active shuttle.

8. A loom comprising a lay rock shaft, a main lay section having a raceway supported by and swinging with said shaft, a shuttle box lay section supported to swing with, and with respect to, the main lay section, a plurality of shuttle boxes on the box lay section, any one of which may be aligned with the raceway by shifting the said section, means for swinging the main lay section and therewith the box lay section, means for swinging the box lay section at predetermined times with respect to the main lay section to shift either shuttle box thereon as required into alignment with the raceway, and a shoe on the lay rock shaft, a picker stick having a rocker resting on the shoe, and means for swinging the picker stick in parallelism with the rock shaft to effect its picking movement and for swinging the picker stick transversely of the rock shaft to cooperate with the active shuttle.

9. A loom comprising a lay rock shaft, a main lay section having a raceway supported by and swinging with said shaft, a shuttle box lay section, a plurality of shuttle boxes

on the box lay section, any one of which may be aligned with the raceway by shifting the said section, means for swinging the main lay section and therewith the box lay section, 5 means for swinging the box lay section at predetermined times with respect to the main lay section to shift either shuttle box thereon as required into alignment with the raceway, and a shoe on the lay rock shaft, a picker stick having a rocker resting on the shoe, the cooperating faces of the shoe and rocker being relatively curved both longitudinally and transversely to permit the upper effective end of the picker stick to move in substantial parallelism with the rock shaft and thereby with the lay during its picking movement when cooperating with either active shuttle, and means for swinging the picker stick in parallelism with the rock shaft to effect its picking movement and for swinging it transversely of the rock shaft to bring it into cooperation with the active shuttle.

10. A loom comprising a lay rock shaft, a main lay section having a raceway supported by and swinging with said shaft, a shuttle box lay section, a plurality of shuttle boxes on the box lay section, any one of which may be aligned with the raceway by shifting the said section, means for swinging the main lay section and therewith the box lay section, 20 means for swinging the box lay section at predetermined times with respect to the main lay section to shift either shuttle box thereon as required into alignment with the raceway, and a shoe on the lay rock shaft, a picker stick having a rocker resting on the shoe, the upper face of the shoe being flat and parallel with the rock shaft and the cooperating face of the rocker being curved both longitudinally and transversely to permit the upper effective end of the picker stick to move in substantial parallelism with the rock shaft and thereby with the lay during its picking movement when cooperating with either active shuttle, and means for swinging the picker stick in parallelism with the rock shaft to effect its picking movement and for swinging it transversely of the rock shaft to bring it into cooperation with the active shuttle.

11. A loom comprising a lay rock shaft having a shoe, a picker stick having a rocker resting on the shoe, the cooperating faces of the shoe and rocker being relatively curved both longitudinally and transversely to permit the upper effective end of the picker stick to move in substantial parallelism with the rock shaft in either of a transverse plurality of positions, and means for swinging the picker stick in parallelism with the rock shaft to effect its picking movement and for shifting the upper end of the picker stick transversely of the rock shaft into either of a plurality of transverse positions.

12. A loom comprising a lay rock shaft having a shoe, a picker stick having a rocker

resting on the shoe, the upper face of the shoe being flat and parallel with the rock shaft and the cooperating face of the rocker being curved both longitudinally and transversely to permit the upper effective end of the picker stick to move in substantial parallelism with the rock shaft in either of a transverse plurality of positions, and means for swinging the picker stick in parallelism with the rock shaft to effect its picking movement and for shifting the upper end of the picker stick transversely of the rock shaft into either of a plurality of transverse positions.

13. A loom comprising a lay having a main section with a raceway and a transversely shiftable box section, two shuttle boxes on the box lay section, either of which may be aligned with the raceway by shifting the box lay section, a picker rod for each box mounted on the box lay section in parallelism with the raceway, a picker slideable on each picker rod, a single picker stick shiftable transversely into engagement with the picker of the active shuttle and out of engagement with the picker of the inactive shuttle, and means for effecting the picking movement of the picker stick.

14. A loom comprising a lay having a main section with a raceway and a transversely shiftable box section, two shuttle boxes on the box lay section, either of which may be aligned with the raceway by shifting the box lay section, a picker rod for each box mounted on the box lay section in parallelism with the raceway, a picker slideable on each picker rod, a single picker stick mounted to cause its upper end to move in parallelism with the raceway during its picking movement and between the pickers, means for effecting operative engagement of the picker stick with the picker of the active shuttle and disengagement from the picker of the inactive shuttle, and means for effecting the picking movement of the picker stick.

15. A loom comprising a lay having a main section with a raceway and a transversely shiftable box section, two shuttle boxes on the box lay section, either of which may be aligned with the raceway by shifting the box lay section, a picker rod for each box mounted on the box lay section in parallelism with the raceway, a picker slideable on each picker rod, a single picker stick mounted to cause its upper end to move in parallelism with the raceway during its picking movement and between the pickers, a pin extending transversely from each side of the picker stick at its upper end, a slot in each picker cooperating with the corresponding pin, means for shifting the picker transversely with respect to the box lay section to cause one pin to engage the slot in the picker of the active shuttle and the other pin to disengage the slot of the picker of the inactive shuttle, and means for effecting the picking movement of the picker stick.

16. A loom comprising the construction defined in claim 13, together with a guide for the upper portion of the picker stick extending parallel with the raceway and mounted 5 on the box lay section to move transversely thereof, and means acting upon movement of the box lay section with respect to the main lay section to move the guide transversely and swing the picker stick into cooperation 10 with the picker of the active shuttle and out of cooperation with the picker of the inactive shuttle.

17. A loom comprising a lay having a raceway, a plurality of shuttle boxes at one end 15 of the lay transversely shiftable to bring either into alignment with the raceway, a picker mechanism including a picker stick effective to cooperate with either shuttle box when in alignment with the raceway, and a 20 pick motion acting to effect both the picking movement of the picker stick and the latter portion of its return movement thus to insure proper positioning of the picker mechanism when the boxes shift.

18. A loom comprising a lay having a raceway, a plurality of shuttle boxes at one end 25 of the lay transversely shiftable to bring either into alignment with the raceway, a picker mechanism including a picker stick effective to cooperate with either shuttle box when in alignment with the raceway, and a 30 pick motion including a driven cam and a pick arm connected to the picker stick and rocked by the cam in one direction to effect 35 the picking movement of the picker stick and also rocked by the cam in the opposite direction during the latter part of its return movement thus to insure proper positioning of the picker mechanism when the boxes shift.

19. A loom comprising a lay having a raceway, a plurality of shuttle boxes at one end 40 of the lay transversely shiftable to bring either into alignment with the raceway, a picker mechanism including a picker stick effective to cooperate with either shuttle box when in alignment with the raceway, and a 45 pick motion acting to effect the picking movement of the picker stick and including means for positively effecting the latter portion of 50 the return movement of the picker stick thus to insure proper positioning of the picker mechanism when the boxes shift.

20. A loom comprising a lay rock shaft, a main lay section having a raceway supported 55 by and swinging with said shaft, a shuttle box lay section, a plurality of shuttle boxes on the box lay section, any one of which may be aligned with the raceway by shifting the said section, means for swinging the main 60 lay section and therewith the box lay section, means for swinging the box lay section at predetermined times with respect to the main lay section to shift either shuttle box thereon as required into alignment with the 65 raceway, the adjacent ends of the main and

box lay section presenting extended smooth abutting faces and means extending through and holding said faces in contact while permitting the swinging movement of the box 70 lay section.

21. A loom comprising a lay rock shaft, a main lay section having a raceway supported from and swinging with said shaft, a shuttle box lay section supported from and swinging with, and with respect to, said shaft, two 75 shuttle boxes on the box lay section, either of which may be aligned with the raceway by shifting the said section, means for swinging the main lay section and therewith the box 80 lay section, means for swinging the box lay section at predetermined times with respect to the main lay section to shift either shuttle box thereon as required into alignment with the raceway, a picker for each 85 box slidable longitudinally on the box lay section, a single picker stick supported on the lay rock shaft, means for swinging the picker stick transversely into engagement with the picker of the active shuttle and out of engagement with the picker of the inactive shuttle, and means for effecting the picking 90 movement of the picker stick.

22. A loom comprising a lay rock shaft, a main lay section having a raceway supported by and swinging with said shaft, a shuttle box lay section supported by and swinging with, and with respect to, said shaft, two shuttle boxes on the box lay section, either one of which may be aligned with the raceway by shifting the said section, means for swinging the main lay section, a lever fulcrumed on the main lay section having one arm engaging the box lay section to shift it in either direction and having its other arm provided with a follower, a cam member mounted for bodily movement between two positions on the loom frame and having a groove for said follower, means for shifting the cam member from one position to the other as required to shift the shuttle 105 boxes, the cam follower riding in the groove of the cam member during the swing of the main lay section to prevent swinging movement of the box lay section relatively thereto when the cam member is in either of the said 110 positions, the follower bearing against one wall of the groove when the cam member is in one position and against the other wall when the cam member is in the other position and each of said walls, when in the said 115 positions, being concentric with the axis of the lay rock shaft.

23. A loom comprising a lay rock shaft, a lay having a main section with a raceway and a transversely shiftable box section, two 120 shuttle boxes on the box lay section, either of which may be aligned with the raceway for shifting the box lay section, a picker for each box slidable longitudinally thereof, a single picker stick mounted to cause its upper 125

- end to move in parallelism with the raceway during its picking movement and between the pickers, a guide for the upper portion of the picker stick extending parallel with the raceway and mounted on the box lay section to move transversely thereof, means acting upon movement of the box lay section with respect to the main lay section to move the guide transversely and swing the picker stick into cooperation with the picker of the active shuttle and out of cooperation with the picker of the inactive shuttle, and means for effecting the picking movement of the picker stick.
24. A loom comprising the construction defined in claim 23, in which the said guide is pivoted on an axis parallel with the raceway and is provided with a projecting arm, a second arm projecting from the lay rock shaft and a link connecting said arms to effect the said transverse movement of the guide when the box lay section is swung with respect to the main lay section.
25. A loom comprising the construction defined in claim 23, in which the said guide is pivoted on an axis parallel with the raceway and is provided with a projecting arm, a second arm projecting from the lay rock shaft, a link connecting said arms to effect the said transverse movement of the guide when the box lay section is swung with respect to the main lay section, and a give-way element in the said connections between the guide and the lay rock shaft.
26. A loom comprising a lay having a main section with a raceway and a transversely shiftable box section, a plurality of shuttle boxes on the box lay section, any one of which may be aligned with the raceway by shifting the said section, a single picker stick, a guide for the upper end of the picker stick mounted in parallelism with the raceway on the box lay section, means for transversely shifting said guide when the box lay section is shifted to shift the picker stick into cooperation with the active shuttle, and means for swinging the picker stick longitudinally of the raceway in each of its transverse positions.
27. A loom comprising a lay having a main section with a raceway and a transversely shiftable box section, a plurality of shuttle boxes on the box lay section, any one of which may be aligned with the raceway by shifting the said section, a single picker stick, a guide for the upper end of the picker stick pivotally mounted on the box lay section on an axis parallel with the raceway, means acting upon the movement of the box lay section with respect to the main lay section to swing the guide transversely and swing the picker stick into cooperation with the active shuttle and out of cooperation with an inactive shuttle, and means for effecting the picking movement of the picker stick.
28. A loom comprising the construction defined in claim 27, in which the guide is composed of a pair of members extending parallel to the raceway and between which the picker stick swings, the inner surfaces of which members are convex so that both may maintain guiding contact with the picker stick in all positions.
29. A loom comprising the construction defined in claim 13, together with means controlled by the relative movement between the main lay section and the box lay section acting to effect the transverse shift of the picker stick.
30. A loom comprising a lay having a main section with a raceway and a transversely shiftable box section, two shuttle boxes on the box lay section, either of which may be aligned with the raceway by shifting the box lay section, a single picker stick shiftable transversely into cooperation with the active shuttle and out of cooperation with the inactive shuttle, and means for effecting the picking movement of the picker stick.
31. A loom comprising the construction defined in claim 30, together with means for positively effecting the latter portion of the return movement of the picker stick.
32. A loom comprising a lay having a main section with a raceway and a transversely shiftable box section, two shuttle boxes on the box lay section, either of which may be aligned with the raceway by shifting the box lay section, a pair of transversely adjustable stops on one section and a lug extending from the other section between said stops for limiting the relative transverse shift of the said lay sections.
33. A loom comprising a lay having a main section with a raceway and a transversely shiftable shuttle box section, a single shuttle guiding throat at the end of the raceway on the main lay section, and a plurality of shuttle boxes on the box lay section, any one of which may be aligned with the said throat and the raceway by shifting the box lay section, the shuttle guiding throat presenting a front wall and a back wall each curved outwardly and acting upon the shift of the box section to engage the nose of a slightly mispositioned shuttle and force it into its box.
34. A loom comprising a lay having a main section with a raceway and a transversely shiftable shuttle box section, a single shuttle guiding throat at the end of the raceway on the main lay section, a plurality of shuttle boxes on the box lay section, any one of which may be aligned with the said throat and the raceway by shifting the box lay section, the shuttle guiding throat presenting a rear wall and a front wall, with the front wall both longitudinally and transversely adjustable on the raceway, and means for locking the said wall in adjusted position.

35. A loom comprising a lay having a main section with a raceway and a transversely shiftable shuttle box section, a single shuttle guiding throat at the end of the raceway on the main lay section having a front wall comprising a main section and an outer end section, means for longitudinally adjusting the said wall sections with respect to each other and for locking the same in adjusted position, and a plurality of shuttle boxes on the box lay section, any one of which may be aligned with the said throat and the raceway by shifting the box lay section.

36. A loom comprising a lay having a main section with a raceway and a transversely shiftable shuttle box section, a single shuttle guiding throat at the end of the raceway on the main lay section having a front wall comprising a main section and an outer end section having an outwardly curved shuttle engaging and positioning face, means for longitudinally adjusting the said wall sections with respect to each other and for locking the same in adjusted position, and a plurality of shuttle boxes on the box lay section, any one of which may be aligned with the said throat and the raceway by shifting the box lay section.

37. A shifting shuttle box loom comprising a lay, two shuttle boxes on the lay separated by a central wall member in which the said member is composed of two parallel transversely adjustable sections, means for securing said transversely adjustable sections in adjusted position and means for securing said member when thus adjusted to the lay.

38. A shifting shuttle box loom comprising the construction defined in claim 37, in which the two sections of the central wall member have their adjacent and opposite ends bevelled to provide for the relative transverse adjustment thereof.

39. A loom comprising a lay rock shaft, a main lay section having a raceway supported by and swinging with said shaft, a shuttle box lay section, a plurality of shuttle boxes on the box lay section, any one of which may be aligned with the raceway by shifting the said section, means for swinging the main lay section and therewith the box lay section, means for swinging the box lay section at predetermined times with respect to the main lay section to shift either shuttle box thereon as required into alignment with the raceway, the said means for swinging the box lay section including a give-way connection acting to prevent a smash if the box lay section is held against movement when said means comes into action.

40. A loom comprising a lay having a main section with a raceway and a transversely shiftable shuttle box lay section, a plurality of shuttle boxes on the box lay section, any one of which may be aligned with

the raceway by shifting the box lay section and means for shifting the box lay section including a give-way connection acting to prevent a smash if the box lay section is held against movement when said means comes into action.

In testimony whereof, I have signed my name to this specification.

CARL D. BROWN.
